PUMP

Robert P. Miller, San Gabriel, Calif.

Application July 15, 1939, Serial No. 284,720

13 Claims. (Cl. 103—240)

This invention relates to pumping a fluid by fluid pressure; the fluid which is to be pumped being herein referred to as production fluid and the fluid under pressure which pumps the production fluid being herein referred to as displacement fluid.

The invention is particularly applicable to petroleum wells in which the production fluid is from a production zone of the well and the displacement fluid is any suitable gas supplied under pressure from any desired source. In practice, a production string may extend through usual well casing to the production zone of the well with displacement fluid supplied via the annular space at the exterior of the production string, or the production string may surround an inner conduit through which displacement fluid is supplied.

It is an object of the invention to shut off admission of displacement fluid to the lower end of the production string so that production fluid may rise in the production string, this being the filling period; and to then admit displacement fluid to the lower end of the production string for elevating the column of production fluid, this being the discharge period. More particularly it is an object of the invention to control alternate shut off and admission of displacement fluid by reciprocating an operating element from the earth's surface, so that while the operating element is lowered admission of displacement fluid is shut off, and while the operating element is lifted displacement fluid is admitted.

By lifting the operating element to admit displacement fluid, the column of fluid which is elevated via the production string tends to maintain the operating element in its lifted position; whereas if lowering the operating element admitted displacement fluid, the column of fluid then elevated via the production string would tend to displace the operating element from its lowered operative position.

It is a further object of the invention to automatically control reciprocation of the operating element and to independently adjust the time intervals during which the operating element is elevated and lowered respectively, so as to provide any desired filling period during which admission of displacement fluid is shut off and any desired discharge period during which displacement fluid is admitted to the production string.

It is a still further object of the invention to adjustably tension the means which suspends the operating element, so that irrespective of

stretch inherent in that particular suspension means which is being used, reciprocation of the suspension means permits positive shifting of the operating element to either lowered or elevated position, rather than merely alternately stretching and relieving tension in the suspension means without reciprocating the operating element.

It is a still further object of the invention to conveniently indicate the weight of the operating element which is carried by the suspension means, so that difference in indicated weight when the suspension means is raised and lowered will indicate whether the operating element is being reciprocated for controlling admission of displacement fluid or is remaining in its lowered position while reciprocation of the suspension means merely alternately stretches and relieves tension in the suspension means.

It is a still further object of the invention to adjust the stroke of the suspension means so as to reciprocate the operating element between such lowered position as will shut off admission of displacement fluid and such elevated position as will admit displacement fluid to the production string.

It is a still further object of the invention to control admission of displacement fluid at any desired level in the production string, with that portion of the production string which depends from the control means comprising conduits which communicate with one another at their lower ends, and the upper ends of which communicate respectively with the control means and with that portion of the production string which extends upwardly from the control means to the earth's surface; and to arrange the control means so that lowering the operating element not only shuts off admission of displacement fluid to the depending conduit which communicates with the control means but also vents said conduit, and lifting the operating element not only admits displacement fluid to the depending conduit which communicates with the control means but also closes the vent in said conduit.

By this arrangement, when the operating element is lowered, production fluid rises in both conduits which depend from the control means, admission of displacement fluid being shut off and the vent for the depending conduit which communicates with the control means being open to permit escape of displacement fluid of a preceding discharge period; and when the operating element is lifted, displacement fluid is supplied via the depending conduit which com-

municates with the control means, with the vent for said conduit closed. The displacement fluid thus flows downwardly through the depending conduit which communicates with the control means, displacing production fluid from said conduit and then elevating, via the depending conduit which communicates with the upper portion of the production string, that column of production fluid standing in said conduit and that column of production fluid which has been displaced from the first mentioned depending conduit. The displacement fluid then rises in the depending conduit which communicates with the upper portion of the production string, raising the column of production fluid which is in said conduit in advance of said displacement fluid and thereby elevating said production fluid through the upper portion of the production string for discharge at the earth's surface.

By directing the displacement fluid downwardly through the depending conduit which communicates with the control means and thence upwardly through the depending conduit which communicates with the upper portion of the production string, the column of production fluid standing in both conduits is elevated during each discharge period, and the level at which the lower ends of the two depending conduits communicate may be at any desired level below the control means. If displacement fluid is supplied to the control means from the annular space at the exterior of the production string, the control means may thus be above the production zone of the well, with a packer below the control means shutting off the annular supply space from the production zone, and the conduits which depend from the control means may extend to any desired level within said production zone. If the production string is a double-string with displacement fluid supplied to the control means via the annular space between the two strings, the control means may be above the level at which the double-string ends, with the conduits which depend from the control means of a diameter adapting them for reception in the depending portion of the well bore which extends into the production zone and which may be of reduced diameter below the double-string.

By venting (during the filling period) that depending conduit which communicates with the control means, the displacement fluid which remains in said depending conduit after admission of displacement fluid has been shut off at the end of the preceding discharge period, escapes from said depending conduit so that production fluid is free to rise in both the conduits which depend from the control means. The hydrostatic head of that volume of production fluid which constitutes the slug which is to be elevated during the next discharge period, is thus materially less than if the same volume of production fluid entered only that depending conduit which communicates with the upper portion of the production string. Back-pressure against the formation such as would retard production is thus appreciably reduced.

It is a still further object of the invention to control the volume of production fluid which enters the production string at each filling period, irrespective of the time interval of said filling period. By this arrangement, the time intervals of alternate filling and discharge may be adjusted for maximum economy of operation,

while maintaining total production within a pre-determined limit.

It is a still further object of the invention to adjust the volume of production fluid which enters the production string during each filling period, so that total production will be in accordance with proration for the particular well, irrespective of the particular timing which is employed.

Further objects of the invention will be readily understood from the following description of the accompanying drawings, in which:

Fig. 1 is a diagrammatic view of the upper end of a well equipped for pumping in accordance with the present invention, showing the actuating and control mechanism for reciprocating an operating element in the well.

Fig. 2 is an axial section through the lower end of the well, showing the pumping mechanism and its operating element and also showing kick-over means.

Fig. 14 is a transverse section on the line 14—14 of Fig. 13.

Figs. 15 and 16 are axial sections on the lines 15—15 and 16—16 respectively of Fig. 14.

Fig. 17 is a transverse section on the line 17—17 of Fig. 15.

Fig. 18 is a transverse section on the line 18—18 of Fig. 16.

By way of example, the invention is illustrated and described in connection with the pumping of petroleum wells, the pump being installed in a production string A which in the illustrated embodiment of the invention has an annular space B at the exterior of the production string through which gas under pressure and constituting displacement fluid is supplied to a control means C which is mounted in the production string adjacent its lower end.

The control means C is actuated by an operating element D which is suspended from a flexible line E; and at the earth's surface the line is raised and lowered by actuating means F which has control mechanism G.

That portion of the production string which depends from the control means C preferably comprises a pair of conduits H and I which are preferably arranged one within the other; and the displacement fluid which is admitted via the control means flows downwardly through one of said conduits, which at its lower end communicates with the second depending conduit, and then rises through said second depending conduit, which at its upper end communicates with that portion of the production string which extends upwardly from the control means to the earth's surface.

The actuating means F which raises and lowers the line E is preferably operated by fluid pressure. For this purpose, a vertical cylinder 1 is positioned at the earth's surface alongside the well, and a piston 2 is adapted for reciprocation in the cylinder and is connected to an upwardly projecting piston rod 3. A sheave 4 is journaled in a frame 5 which is connected to the rod 3, and the frame 5 has guide means 6 adapted for reciprocation in guideways 7 which project upwardly from the cylinder 1. Fluid pressure is alternately supplied and exhausted from the lower end of the cylinder 1 for alternately raising and lowering the sheave 4; and adjustable stops 9-10 which are adapted for respective engagement by the upper end of the frame 5 and by the upper end of the cylinder 1 limit raising and lowering of the sheave 4.

The line E is raised and lowered by reciprocating the sheave 4. Means are preferably provided for adjusting the tension of the line E, i. e. for adjusting that portion of the weight of the operating element D which is supported by the control means C when said operating element is in lowered position; and means are preferably provided for indicating the weight suspended from the line E. For this purpose, the end 12 of the line E projects upwardly through the upper end of the production string A, preferably via a stuffing box 13, and is connected to a clamp 14, with the line 12 then extending upwardly and over the sheave 4 and thence downwardly to a spool (not shown) on which the dead end of the line is wound. The clamp 14 is suspended from a cable 15 which also extends upwardly and over the sheave 4 and thence downwardly to the lever 16 of a weight indicator 17. By adjusting the point at which the clamp 14 engages the line 12, any desired weight of the operating element D may be supported on the control means C when the line E is lowered, thereby suspending the remainder of the weight of the operating element from the line E so as to maintain any desired tension on the line when it is in its lowered position. The weight suspended from the line E is shown on the weight indicator 17, so that difference in indicated weight when the line is lowered but still carries a portion of the weight of the operating element, and when the line is elevated so that it carries the entire weight of the operating element, indicates whether raising and lowering the line E is properly reciprocating the operating element D to alternately exert desired weight on the control means C and then lift said weight.

The fluid pressure which reciprocates the piston 2 is automatically controlled; and the control mechanism is adjustable, for adjusting the time interval during which fluid pressure is supplied for elevating the piston 2, and for independently adjusting the time interval during which fluid pressure is relieved to permit lowering of the piston.

For this purpose, the fluid pressure which is employed is preferably pressure of the displacement fluid which is utilized for pumping the well and which is supplied from any suitable source to the annular space at the exterior of the production string A. As shown at Fig. 1, the production string A is suspended in well casing 20, with the production string projecting above the well casing via a usual casing head 21. Displacement fluid is supplied to the annular space B between the production string A and the casing 20, via a suitable supply conduit 22. A conduit 23

communicates with the casing head 21, whereby a portion of the displacement fluid, after reduction in pressure, is utilized for reciprocating the piston 2. For this purpose, a pressure reducer 27 is connected to the conduit 23, and a supply conduit 24 leads from the pressure reducer to the lower end of the cylinder 1. An exhaust conduit 25 leads from the conduit 24, preferably to that portion of the production string which projects above the casing head 21 and which is provided with a flow outlet 26.

The control mechanism G alternately admits fluid pressure via conduit 24 to the cylinder 1 and exhausts said fluid pressure via the conduit 25; the control mechanism being automatically actuated and adapted for independent adjustment of the time intervals during which pressure fluid is supplied and exhausted respectively. For this purpose, diaphragm valves 30-31 may respectively control the supply and exhaust conduits 24-25, with fluid pressure which is supplied via conduits 32-33 adapted to respectively open the normally closed valve 30 and close the normally open valve 31. Fluid pressure may be supplied to the conduits 32-33 via a conduit 34 which branches from the pressure reducer 27 and which is preferably provided with a pressure regulator 35; and supply and exhaust of pressure via the conduit 34 is automatically controlled.

For this purpose, a bleeder line 29 may extend from the conduit 34, and the bleeder line may be alternately opened and closed by a valve 36 which may be actuated by usual clock mechanism. For example, a clock mechanism 37 may rotate a disc 38, and the valve 36 may be mounted on a lever 39 which is pivoted at 28 and which during rotation of the disc 38 is alternately spring retracted to open the valve and rides on circumferentially spaced abutments on the disc to close the valve. The abutments are shown as rollers 40 mounted on clips 41 which are adapted for detachable mounting on the disc 38 in any desired circumferentially spaced relation. The speed of rotation of the disc 38 and the circumferential spacing of the rollers 40 is adjusted so that the lever 39 is spring retracted for opening the bleeder valve 36 during successive time intervals of any desired duration, between successive engagements of the lever by the circumferentially spaced rollers.

Means are provided for adjusting the successive time intervals during which the lever 39 rides on the circumferentially spaced rollers for closing the bleeder valve 36. For this purpose a cam 42 on the lever 39 is adapted for engagement by the successive rollers 40 for swinging the lever to close the bleeder valve; and the cam is adjustable to vary the length of its surface which rides on a roller for maintaining the lever in valve-opening position. As an instance of this arrangement, the cam 42 may be adjustable in a slot at the end of the lever 39, preferably by a worm drive 43 which is manually rotated by a knob 44, so that the cam forms a contact surface 45 of adjustable length in the direction of movement of the rollers 40 which cooperate with the cam.

During rotation of the disc 38, the lever 39 is spring retracted between engagement of successive rollers with the cam, thereby opening the valve 36 so that pressure is built up in the conduit 34 and from the conduits 32-33, via the line 29. The valves 30-31 are thus spring actuated

for closing the valve 39 and opening the valve 34, whereby fluid pressure is exhausted from the cylinder 1 to permit retraction of the piston 2 for lowering the line E so that the operating element D actuates the control means C for shutting off admission of displacement fluid, thereby determining the filling period by the time interval between engagement of successive rollers with the cam. During engagement of successive rollers with the cam, the lever 38 closes the bleeder valve 36 so that pressure is built up in the conduit 34 and in the conduits 32-33, thereby opening the valve 30 and closing the valve 34. Fluid pressure is thus supplied to the cylinder 1 for elevating the piston 2 and thus raising the line E so as to lift the operating element D for admitting displacement fluid via the control means C, thereby determining the discharge period by the time interval during which the cam is engaged by a roller.

The time interval for travel of the piston 2 to either its raised or lowered position may be adjusted by needle valves 46-47 in the conduits 24-25 respectively; and the time interval during which the piston then remains in lowered position, i. e. the filling period, may be adjusted by adjusting the speed of the disc 38 and the spacing of the rollers 40; and the time interval during which the piston 2 remains in elevated position, i. e. the discharge period, may be adjusted independently of the filling period by adjusting the length of the contact surface 45 which is engaged by the successive rollers.

The control means C which is actuated by raising and lowering the operating element D may be arranged as shown at Fig. 2 and as shown in detail at Figs. 7 to 9. This construction is applicable where the production string A comprises a single string of tubing, with displacement fluid supplied via the annular space B between the tubing string and the surrounding well casing 20.

As an instance of this arrangement, the production string comprises a string of tubing 51, with an obstruction 50 suspended from this tubing string and forming the control means C, and with a continuation of the tubing string depending from the obstruction as shown at 52 and forming the depending conduit H which surrounds the depending conduit I. The obstruction 50 is axially bored from its upper end to form a cylinder 53 which terminates short of the lower end of the obstruction and communicates laterally with a bore 54 which opens through the lower end of the obstruction. The upper end of the bore 54 communicates with the cylinder 53 via a transverse bore 55 which is in spaced relation above the lower end of the cylinder; and the transverse bores 56 provide communication between the exterior of the production string and the cylinder 53, at a point spaced below the point of communication between the bore 55 and the cylinder. A plurality of bores 57 extend into the obstruction 50 from its upper end, and at their lower ends communicate with a common bore 58 which opens through the lower end of the obstruction 50. A transverse bore 59 provides communication between the cylinder 53 and one of the bores 57, at substantially the level of the bore 55.

The conduit I communicates with one or the other of the bores 54-58, and is shown as a pipe 60 of appreciably smaller diameter than the tubing 52 and depending from the bore 58 to any desired level in said tubing; and at its lower

end the pipe 60 is open to the bore of the tubing 52 to provide communication between the conduits H-I. The conduit H thus communicates with the control means C via the bore 54 while the conduit I communicates via the bores 57-58 with the upper portion of the production string A; although if desired the pipe 60 may depend from the bore 54, in which case the conduit H would communicate with the upper portion of the production string via the bores 57-58 while the conduit I would communicate with the control means via the bore 54.

Below the level of communication between the conduits H-I a foot valve 61 is preferably provided in the tubing 52; and below this foot valve a fluid screen 62 depends from the tubing 52 for entrance of production fluid from a production zone of the well and via a perforated section 63 of the well casing which surrounds the fluid screen. A packer 64 is provided in the annular space B between the production string and the surrounding well casing, at a point below the bores 56 of the control means and above the perforated well casing 63. Displacement fluid supplied via this annular space is thus shut off from the production zone of the well, and is adapted for admission via the bores 56 of the control means C. The control means C is positioned above the production zone, while the conduits H-I which depend from the control means may extend to any desired level within the production zone.

Reciprocation of the operating element D admits displacement fluid via the bores 56 to the cylinder 53 and thence to the bore 54 while shutting off communication between the transverse bores 55-59; or shuts off communication between the bores 56 and the cylinder 53 while providing communication between the transverse bores 55-59 for venting the bore 54 via said transverse bores and thence via the communicating bore 57.

For this purpose, a piston valve 65 is adapted for reciprocation in the cylinder 53 and is suspended from a valve stem 66 which projects through a closure 67 for the upper end of the cylinder. The valve stem has an abutment head 68 and a spring 69 tends to retract the valve to its upper limit of movement, which is its position when opening the bores 56 to the cylinder 53. A guide 70 preferably surrounds the valve stem 66 for guiding the reciprocating operating element D into engagement with the head 68.

When the line E is lowered, the operating element D which is suspended therefrom, depresses the head 68 and projects the valve 65 against the tension of its spring 69, thereby shutting off admission of displacement fluid via the bores 56 and at the same time venting the bore 54. This is the filling period, during which production fluid opens the foot valve 61 and rises in the conduits 52-60. Depending upon the formation pressure and the time interval before the line E is again elevated for retracting the valve 65 by its spring 69, the production fluid which rises in the conduit 60 may then rise in the bores 57 and may reach a level in the production string A above the control means C before the end of the filling period.

When the line E is again elevated, the operating element D is also raised so that the valve 65 is retracted by its spring 69, thereby closing the vent at 55-59 and admitting displacement fluid via 56-53-54. This is the discharge period, during which pressure of the incoming

displacement fluid is exerted via bores 53-54 against the production fluid in the conduit 52, thereby closing the foot valve 61 and lowering the level of the production fluid which is trapped in the tubing 52 above the closed foot valve, for elevating production fluid via the pipe 60 and the bores 57 and thence via the tubing 51 for discharge at the earth's surface via the outlet 26.

When the line E is again lowered, displacement fluid which is trapped in the bore 54 and in the tubing 52 above the lower end of the pipe 60, is vented via 55-59 and the production fluid again opens the foot valve 61 for admission of said production fluid to the conduits 52-60 for repeating the cycle of operation.

If desired, means may be provided whereby during the discharge period displacement fluid may be supplied at any desired pressure via the annular space B, with its rate of flow regulated during its passage via the bores 53-54 so that irrespective of the pressure of said fluid it will be supplied to the tubing 52 and thence to the pipe 60 at a rate of flow at which it will not blow through the slug of production fluid which is being elevated via the tubing 51 in advance of said displacement fluid.

For this purpose, the rate of flow of displacement fluid from the bore 54 into the tubing 52 may be regulated by suspending a pipe 73 of predetermined bore and length from the bore 54. Pipes 73 of different bore and length may be interchangeably employed by providing a threaded connection 74 between the bore 54 and the pipe 73; and the pipe 73 which is employed has a bore and length providing predetermined restriction to flow therethrough. This construction, i. e. employing the pipe 73, is particularly applicable where displacement fluid is supplied at relatively high pressure at the earth's surface or is supplied from an upper pressure zone of the well which is being pumped.

In the case of high pressure supply at the earth's surface, the necessity of reducing pressure before admitting the displacement fluid to the annular space B is thus eliminated. The displacement fluid may be admitted to the space B at any high pressure at which it is furnished from the source of supply; and a pipe 73 is employed having a bore and length, which in accordance with pressure of the displacement fluid, restricts flow via said pipe so that the displacement fluid is discharged into the tubing 52 at a restricted rate of flow whereby it will elevate production fluid in advance of said displacement fluid and via 60-58-57-51 without danger of blowing through the slug of production fluid.

In similar manner, when displacement fluid is supplied to the annular space B from an upper pressure zone of the well, the displacement fluid may be supplied via 56-53-54 at whatever pressure it comes from the pressure zone, a pipe 73 being employed, which in accordance with pressure of said displacement fluid, restricts flow via said pipe so that the displacement fluid is discharged into the tubing 52 at a restricted rate of flow which will eliminate possibility of the displacement fluid blowing through the slug of production fluid which it is elevating via the tubing 51.

When the production string is a double-string of tubing, the displacement fluid may be supplied via the annular space between the tubing strings, with the control means C constructed as shown at Figs. 10 to 12. As an instance of this arrangement, a string of tubing 51a is sur-

rounded by a second tubing string 75, with the tubing 51a forming the production string A, and with the annular space between the tubing strings 51a-75 forming the annular space B through which displacement fluid is supplied from a suitable source at the earth's surface.

The arrangement at the earth's surface is not illustrated, being of usual construction comprising a casing head on well casing which surrounds the outer tubing string 75, with the tubing string 51a projecting above the casing head for discharge of production fluid, and with the annular space B which is between the tubing strings 51a-75, closed to the annular space between the outer tubing string and the surrounding well casing. Displacement fluid is supplied to the annular space B from any desired source, with a portion of the displacement fluid utilized for operating the actuating means F as previously described; and the annular space between the outer tubing string 75 and the surrounding well casing is arranged for discharge of gas from said annular space.

Guide means 76 may be provided between the tubing strings 51a-75; and an obstruction 50a which forms the control means C is suspended from the tubing 51a, with the tubing 75 fixed to the obstruction 50a in spaced relation below its upper end so as to close the lower end of the annular space B. A tubing string 52a, which may be of appreciably smaller diameter than the tubing 75, depends from the obstruction 50a and forms the depending conduit H which surrounds the depending conduit I.

The obstruction 50a is provided with bores arranged similarly to those formed in the obstruction 50 (previously described) and designated by the same reference numerals but with the exponent a, except that the bore 57a which communicates with the transverse bore 59a, is closed at its upper end as shown at 77 and its lower end instead of opening into the bore 58a communicates via lateral port 78 with the annular space at the exterior of the outer tubing string 75. The remainder of the bores 57a communicate at their lower ends with the bore 58a and open through the upper end of the obstruction 50a as previously described. The bores 56a communicate with the annular space B between the tubing strings 51a-75.

A pipe 60a forms the conduit I and depends from the bore 58a, with the pipe 60a (at its lower end which is not shown) communicating with the tubing string 52a, and with a check valve 79 in the upper end of the pipe for a purpose hereinafter described. Production fluid is admitted to the tubing string 52a from a production zone of the well, via a foot valve (not shown), as previously described.

The depending conduits H-I may thus extend into a restricted lower portion of the well bore to any desired level within the production zone, with the double-tubing string 51a-75 terminating above this restricted portion of the well bore and with the control means C also positioned above this restricted portion of the well bore.

A piston valve 65a is adapted for reciprocation in the cylinder 53a for controlling the intake ports 56a and the vent ports 55a-59a. The operation is the same as that explained in connection with Fig. 7, except that during the filling period the vent via 55a-59a discharges via that bore 51a which is closed at its upper end, and thence via port 78 into the annular space at the exterior of the double-tubing string, for dis-

charge from said annular space at the earth's surface.

The double-tubing string as thus described, provides for reduction of back pressure against the formation for insuring maximum production, particularly from wells of low static pressure and from wells which produce a large volume of gas. Gas from the production zone is free to rise in the annular space between the double-tubing string and the surrounding well casing (there being no packer in this annular space as in the construction shown at Figs. 2 and 7); and this gas is discharged at the earth's surface. Development of back pressure against the formation is thus reduced; and if desired a vacuum may be maintained in the gas discharge line at the earth's surface, by usual means (not shown), for insuring discharge of gas and thus reducing back pressure to a minimum.

When the valve 65a is actuated to close the ports 56a and thus terminate the discharge period, the check valve 79 is closed by pressure of the displacement fluid in the tubing string A above the control means C, and therefore only the displacement fluid which is trapped in 52a-54a and in the pipe 60a below the closed check valve, is vented via port 78 to the annular gas discharge space at the exterior of the double-tubing string, without displacement fluid which is in the tubing string A blowing-down via pipe 60a and upwardly via conduit 52a for venting via port 78 (as would be the case if the check valve 79 were not employed). By thus venting only the displacement fluid trapped in 60a-52a-54a, pressure is rapidly reduced at the end of the discharge period, to permit intake of production fluid for quickly inaugurating the next following filling period.

The valve 65a is actuated as previously described in connection with Fig. 7, i. e. by alternately lowering and raising the operating element D relative to the head 68a which is provided on the stem 66a of the valve, with spring 69a yieldably elevating the valve, and with guide means 70a insuring alignment of the operating element with the head of the valve stem.

At Figs. 13 to 18 I have shown a modification whereby the production fluid which enters during the filling period, rises via the conduit I and the control means C to only a predetermined level short of its static or working level, irrespective of the time interval before starting the next following discharge period. This predetermined level may be adjusted; and by thus adjusting the discharge at each discharge period the well production for any desired period of time may be regulated to any desired total volume, while employing any desired time intervals between successive discharge periods.

As an instance of this arrangement, the construction is the same as that shown at Figs. 1 and 2 except for details of the control means C, with corresponding parts indicated by the same reference numerals but with the exponent b. An obstruction 50b which forms the control means C, is suspended from tubing string 51b, with tubing 52b depending from the obstruction 50b and forming the conduit H. Production fluid from the production zone of the well, enters the conduit H via a foot-valve (not shown), and a pipe 60b depends from the obstruction 50b within the tubing 52b and forms the conduit I, all as previously described in connection with Fig. 7.

Piston valve 65b is adapted for reciprocation

in the cylinder 53b which communicates with the bore 54b, and ports 56b communicate with the cylinder 53b and supply displacement fluid from the annular space B when the valve 65b has been spring retracted to its upper limit of movement. The cylinder 53b and its communicating bore 54b are preferably laterally offset from the axis of the obstruction 50b, and at the opposite side of the longitudinal axis of said obstruction a bore 80 extends into said obstruction from its upper end and terminates short of the lower end of said obstruction.

A balanced piston valve 81 is adapted for reciprocation in the bore 80, and when in its lowered position it engages cooperating valve seats 82-83. Lateral ports 84-85 communicate with the bore 80 above the valve seat 82 and below the valve seat 83 respectively, and these ports open into a bore 86 which in turn opens through the upper end of the obstruction 50b and into the tubing 51b. A port 87 communicates with the bore 80 between its valve seats 82-83, and opens into a bore 58b which in turn opens through the lower end of the obstruction 50b. The pipe 60b depends from either of the bores 54b-58b, preferably from the bore 58b.

Opening or closing the valve 81 thus opens or closes the bore of the production string, by opening or closing communication between the port 87 and the ports 84-85, the port 87 communicating via 58b-60b with the bore of the tubing 52b which constitutes the lower portion of the production string, and the ports 84-85 communicating via bore 86 with the bore of the tubing 51 which constitutes the upper portion of the production string. The valve 81 opens or closes the bore of the production string at a level above admission of production fluid and displacement fluid, i. e. production fluid is admitted to the production string via the lower end of the tubing 52b and the pipe 60b, and displacement fluid is admitted to the production string via the pipe 60b, this pipe 60b being a part of the production string, and the fluids rise thence via the bore 58b, which is also a part of the production string, to the level of the valve 81.

A port 55b communicates with the cylinder 53b above the ports 56b, and opens into a bore 88 which in turn opens through the lower end of the obstruction 50b; and a port 59b which is at approximately the same level as the port 55b, provides communication between the cylinder 53b and the bore 80, at a point between the valve seats 82-83.

A stem 66b for the valve 65b, extends upwardly through a closure 67b for the cylinder 53b; and the balanced valve 81 has a stem 90 which projects through a closure 91 for the upper end of the bore 80. When the valve stem 90 is lowered, a piston 92 on said stem is received in a dash-pot 93 which is formed in the closure 91 and which bleeds via restricted outlet 94 to the tubing 51b. A head 68b is provided on the valve stem 66b, with a spring 69b surrounding the valve stem and tending to retract the valve 65b to its upper limit of movement; and the head 68b is also connected to the valve stem 90, through a lost motion connection 95 whereby lowering the operating element D against the head 68b first projects the valve 65b against the tension of its spring so as to close the ports 56b, without moving the balanced valve 81, and then projects the valve 65b so as to open the port 55b to the port 59b and also projects the balanced valve 81 against the retarding action of its dash-pot 93.

so as to engage the valve 81 with its seats 82-83 after a time interval determined by the retarding action of the dash-pot.

When the line E and the operating element D are lowered, admission of displacement fluid via the ports 56b is thus shut-off, thereby terminating the discharge period and inaugurating the filling period, and displacement fluid which remains in 52b and in 60b from the discharge period which has thus been terminated, is discharged into the bore 80 via 88-55b-59b and via 58b-87. Consequently this displacement fluid is vented from the bore 80 via 84 and 85 and thence via 86 and the tubing 51b as the balanced valve 81, retarded by its dash-pot, moves toward closed position; and when the valve 81 finally closes its shut-off the vent for displacement fluid via 84 and 85.

As long as the upper portion of the tubing 52b and the pipe 60b are vented, production fluid may enter the tubing 52b and the pipe 60b, seeking its static or working level. This is the filling period. But instead of this filling period continuing until the rising production fluid reaches its static or working level or until the line E is again elevated for inaugurating the next following discharge period (as in the structure disclosed at Figs. 7 and 13), closing the vent via 84 and 85, after a time interval determined by the retarding action of the dash-pot 93, builds up pressure in the upper portion of the tubing 52b and in the pipe 60b, thereby arresting intake of production fluid short of its static or working level. Therefore, irrespective of the time interval before the line E is again elevated to initiate the next discharge period, only a predetermined volume of production fluid, determined by the retarded closing of the valve 81, will have been trapped above the foot valve (not shown) which is mounted in the tubing 52b below the lower open end of the pipe 60b.

When the line E and the operating element D are then elevated (after any desired time interval) to start the next following discharge period, the valve 65b is retracted by its spring 69b to first close the vent 55b-59b and then admit displacement fluid via the ports 56b; and the valve 81 is also elevated through its connection 95, which delays elevation of the valve until the vent 55b-59b has been closed, with said elevation of the valve 81 raising it from its valve seats 82-83. The displacement fluid which is admitted via the bores 56b thus exerts downward pressure in the tubing 52b, for elevating the predetermined trapped volume of production fluid via 60b-58b-87-80 and thence via 84 and 85 and thence via 86 and the tubing 51b, for discharge at the earth's surface. This is the discharge period.

The volume of production fluid which is elevated during each cycle of operation, is thus determined by the rate of admission of fluid from the production zone with relation to the time interval (as determined by the dash-pot 93) between the start of each filling period and the closing of the valve 81; and this relationship may be adjusted for admitting any desired volume of production fluid, by regulating the retarding action of the dash-pot 93. Such regulation is obtained by adjusting the weight of the operating element D which is exerted upon the head 68b when the line E is lowered. This adjustment may be made by interchanging elements D of different weight so as to employ an element of desired weight, and/or by adjusting the point of clamping engagement between the upper end 12

of the line E and the cable 15 so that any desired weight of the element D is exerted against the head 68b when the line E is lowered, and/or by adjusting the stops 8-10 for limiting reciprocation of the sheave 4 and consequent movement of the line E. In practice the desired adjustment is preferably obtained by selecting an operating element D of predetermined weight. As previously described the weight exerted against the head of the control mechanism is indicated at 17, and thus indicates when the weight exerted against the head 68b has been so adjusted as to provide desired regulation of the retarding action of the dash-pot 93.

15 The various forms of the invention thus far described provide means whereby lowering and raising the line E controls filling and discharge periods for respectively admitting production fluid and for elevating and discharging production fluid at the earth's surface, with the line E automatically reciprocated and adapted for independent adjustment of the time intervals during which it is lowered and raised respectively, and with the construction which is shown at Figs. 13 to 18 providing for controlling the volume of production fluid which is admitted during each filling period, irrespective of the time interval before starting the next following discharge period.

20 During elevation of the line E, its suspended operating element D may be elevated clear of the cooperating heads 68, 68a or 68b, whereby the valve of the control means C is retracted solely by the action of its spring, this construction being shown at Figs. 2, 10 and 13; or if desired, and to prevent the possibility of the valve sticking in its projected position so that its cooperating spring is ineffective to retract it for starting the next discharge period, the operating element D may be positively connected to the cooperating head 68, 68a or 68b. Lowering and raising the line E thus 25 positively actuates the valve of the control means C, both for projecting and retracting the valve; but this positive connection is so arranged that when desired it may be readily released for withdrawing the line E and its operating element D without disturbing the control means C.

30 Such a positive connection is shown at Fig. 7, employed in connection with the head 68, it being understood that the same positive connection may be similarly employed with the head 68a or 68b of Figs. 10 or 13.

35 As an instance of this arrangement, the head 68 is provided with a wedge projection 100 having undercut shoulders 101, and the lower end of the operating element D is provided with longitudinally projecting spring jaws 102 having abutments 103. When the operating element D is first lowered, the wedge 100 spreads the jaws 102 so that the abutments 103 engage beneath the undercut shoulders 101; and during normal reciprocation of the operating element D, the engagement 40 101-103 positively reciprocates the head 68 with the reciprocating operating element. When it is desired to withdraw the operating element D, an abnormal strain is exerted via the line E, thereby spreading the jaws 102 so that their abutments 103 clear the shoulders 101, thus 45 releasing the positive connection between the operating element and the cooperating head. To permit this spreading of the jaws, the undercut shoulders 101 and the cooperating surfaces of the abutments 103 are preferably slightly tapered.

50 If desired, the line E which extends into the production string of the well, may be employed, in addition to its function of reciprocating the

operating element D) for suspending any desired apparatus in the production string. For example, and as shown at Fig. 10, the operating element D may be made in sections 105-106 having threaded couplings 107 whereby apparatus such as a pressure recorder 108, provided at its ends with similar couplings, may be detachably mounted between the sections 105-106.

I claim:

1. In combination, a well string for production fluid having an annular space for displacement fluid surrounding the well string, the lower end of the well string communicating with a production zone of the well for admitting production fluid to the well string, a packer at the lower end of the annular space, a passageway between the annular space and the lower portion of the well string, a by-pass between the upper portion of the passageway and the well string, and a valve shiftable to position opening the annular space to the passageway and closing the by-pass, or shiftable to position closing the annular space to the passageway and opening the by-pass.

2. In combination, a well string for production fluid and a second well string for displacement fluid surrounding one another in a well bore with an annular space surrounding the outer well string and communicating at its lower end with a production zone of the well, the lower end of the first well string communicating with said production zone for admitting production fluid to the first well string, an obstruction in the first well string having a bore closed at one end and open at its opposite end for communication with the lower portion of the first well string, the obstruction having a port in the wall of the bore communicating with the bore of the second well string, the obstruction having a by-pass communicating with the bore between the port and the open end of the bore, the obstruction having second ports in the wall of the bore communicating respectively with the by-pass and the annular space, and a piston valve adapted for reciprocation in the bore, for closing the first port and shifting the piston valve clear of the second ports for communication therebetween when the piston valve is moved in one direction, and for closing the second ports and shifting the piston valve clear of the first port for communication between the bore of the second well string and the lower portion of the first well string when the piston valve is moved in the opposite direction.

3. In combination, a well string, means in the well controlling alternate admission of production fluid and displacement fluid to the well string for pumping production fluid via the well string during admission of displacement fluid, operating means adapted for reciprocation in the well for controlling operation of the control means by alternately exerting and relieving weight of the operating means on the control means, the control means including means operable by weight of the operating means exerted on the control means for terminating admission of production fluid at a time interval after inaugurating admission thereof and before subsequently admitting displacement fluid, means for varying said time interval by adjusting weight of the operating means exerted on the control means, and means for adjusting weight of the operating means exerted on the control means.

4. In combination, a well string, means in the well controlling alternate admission of production fluid and displacement fluid to the well string for pumping production fluid via the well string

during admission of displacement fluid, operating means adapted for reciprocation in the well for controlling operation of the control means by alternately exerting and relieving weight of the operating means on the control means, the control means including means operable by weight of the operating means exerted on the control means for terminating admission of production fluid at a time interval after inaugurating admission thereof and before subsequently admitting displacement fluid, means for varying said time interval by adjusting weight of the operating means exerted on the control means, and means for indicating weight of the operating means exerted on the control means.

5. In combination, a well string, means in the well controlling alternate admission of production fluid and displacement fluid to the well string for pumping production fluid via the well string during admission of displacement fluid, operating means adapted for reciprocation in the well for controlling operation of the control means by alternately exerting and relieving weight of the operating means on the control means, the control means including means operable by weight of the operating means exerted on the control means for terminating admission of production fluid at a time interval after inaugurating admission thereof and before subsequently admitting displacement fluid, means for varying said time interval by adjusting weight of the operating means exerted on the control means, and means for indicating weight of the operating means exerted on the control means.

6. In combination, a well string, means in the well for pumping production fluid via the well string, means in the well for controlling the pumping means, operating means adapted for reciprocation in the well for controlling operation of the control means by alternately exerting and relieving weight of the operating means on the control means, means for suspending and reciprocating the operating means in the well, and means for adjusting the suspension means for adjusting weight of the operating means exerted on the control means.

7. In combination, a well string, means in the well for pumping production fluid via the well string, means in the well for controlling the pumping means, operating means adapted for reciprocation in the well for controlling operation of the control means by alternately exerting and relieving weight of the operating means on the control means, means for suspending and reciprocating the operating means in the well, and means cooperating with the suspension means for indicating weight carried by the suspension means.

8. In combination, an oil well, means in the well for producing the well, a weight, flexible means for suspending the weight in the well for cooperation with the producing means for controlling operation of the producing means, and means for indicating the amount of the weight carried by the suspension means.

9. In combination, a well string adapted for alternate admission of production fluid and displacement fluid adjacent the lower end of the well string for pumping production fluid via the well string by the displacement fluid, a first valve adjacent the lower end of the well string controlling admission of displacement fluid, a second valve opening and closing the bore of the well string at a level above admission of said fluids;

and operating means controlling the valves, so that while the first valve is open and for a time interval after closing the same the second valve is open, and throughout the remainder of the time interval during which the first valve is closed the second valve is closed.

10. In combination, a well string adapted for alternate admission of production fluid and displacement fluid adjacent the lower end of the well string for pumping production fluid via the well string by the displacement fluid, a first valve adjacent the lower end of the well string controlling admission of displacement fluid, a second valve opening and closing the bore of the well string at a level above admission of said fluids, and operating means controlling the valves, so that while the first valve is open and for a time interval after closing the same the second valve is open, and throughout the remainder of the time interval during which the first valve is closed the second valve is closed, said operating means including means for adjusting the time interval after closing the first valve during which the second valve is open.

11. In combination, a well string adapted for alternate admission of production fluid and displacement fluid adjacent the lower end of the well string for pumping production fluid via the well string by the displacement fluid, a first valve adjacent the lower end of the well string controlling admission of displacement fluid, a second valve opening and closing the bore of the well string at a level above admission of said fluids, and operating means independently controlling the time intervals during which the first valve is open and closed respectively, said operating means controlling the second valve, so that while the first valve is open and for a time interval after closing the same the second valve is open, and throughout the remainder of the time interval during which the first valve is closed the second valve is closed.

12. In combination, a well string adapted for alternate admission of production fluid and displacement fluid adjacent the lower end of the

well string for pumping production fluid via the well string by the displacement fluid, a first valve adjacent the lower end of the well string controlling admission of displacement fluid, a second valve opening and closing the bore of the well string at a level above admission of said fluids, and operating means independently controlling the time intervals during which the first valve is open and closed respectively, said operating means controlling the second valve, so that while the first valve is open and for a time interval after closing the same the second valve is open, and throughout the remainder of the time interval during which the first valve is closed the second valve is closed, and said operating means including means for adjusting the time interval after closing the first valve during which the second valve is open.

13. In combination, a well string for production fluid and a space for displacement fluid surrounding one another, the lower end of the well string communicating with a production zone of the well for admitting production fluid to the well string, a passageway between the displacement fluid space and the lower portion of the well string, a by-pass between the lower and upper portions of the well string, a first valve shiftable to open position for opening the displacement fluid space to the passageway and closing the by-pass, or shiftable to closed position for closing the displacement fluid space to the passageway and opening the by-pass, a second valve opening and closing the bore of the well string between the upper end of the well string and the level at which the by-pass communicates with the upper portion of the well string, and operating means controlling the valves, so that while the first valve is shifted to open position and for a time interval after shifting the same to closed position the second valve is open, and throughout the remainder of the time interval during which the first valve is shifted to closed position the second valve is closed.

ROBERT P. MILLER.
